(57) **CLAIM**

The ornamental design for a dog toy, as shown and described.

DESCRIPTION

FIG. 1 is a perspective view of my new dog toy design;

FIG. 2 is a top view thereof;

FIG. 3 is a bottom view thereof; and,

FIG. 4 is a further top view thereof with an attachment portion of my new dog toy design removably engaged with a main portion of my new dog toy design.

The broken lines shown are included for the purpose of illustrating portions of the article that form no part of the claimed design. Additionally, the appearance of any portion of the article between the break lines forms no part of the claimed design.
